[57] CLAIM

The ornamental design for a protector for a wrist watch lens, as shown and described.

DESCRIPTION

FIG. 1 is a front perspective view of a protector for wrist watch lens showing my new design, the broken lines showing the user's hand and wrist watch or the like are for illustrative purposes only, and form no part of the claimed design;

FIG. 2 is a top view of my design, the broken lines showing the wrist watch are for illustrative purposes only, and form no part of the claimed design;

FIG. 3 is a bottom view thereof, the broken lines showing the wrist watch are for illustrative purposes only, and for no part of the claimed design;

FIG. 4 is a left side view thereof, the broken lines showing the wrist watch are for illustrative purposes only, and form no part of the claimed design;

FIG. 5 is a right side view thereof, the broken lines showing the wrist watch are for illustrative purposes only, and form no part of the claimed design;

FIG. 6 is a rear view thereof, the broken lines showing the wrist watch are for illustrative purposes only, and form no part of the claimed design;

FIG. 7 is a front view thereof, the broken lines showing the wrist watch are for illustrative purposes only, and form no part of the claimed design; and,

FIG. 8 is a front perspective view thereof showing the cross member of the design being moved toward the top of the watch face of the like so as to better expose the watch face of the like, the broken lines showing the user's hand and wrist watch or the like are for illustrative purposes only, and form no part of the claimed design.
